UNITED STATES PATENT OFFICE.

PEYTON ROWAN, OF LOS ANGELES, CALIFORNIA.

MULTIPLE-RECORD-PLAYING PHONOGRAPH.

Application filed September 13, 1923. Serial No. 662,373.

This invention relates to phonographs and the general object of the invention is to produce a machine of simple construction which is capable of playing a plurality of records in succession by automatically removing the record being played and substituting a new record for it; also to provide a machine of this type with a magazine for holding the records which are to be played, and to provide automatic means for enabling the magazine to cooperate with the platen which supports the record being played, so as to facilitate the operation of the automatic mechanism of the machine in effecting the return of the played record to the magazine and in substituting another record taken from the magazine.

As a machine of this type including a magazine for the records might be used without having the magazine completely filled with records, one of the objects of my invention is to enable the machine to continue to operate automatically in case a record happens to be absent from its place in the magazine.

A further object of the invention is to provide means to enable the operator of the instrument to stop the playing of any record at will before being completely played, and to construct the automatic mechanism in such a way that when the playing of a record is suddenly stopped as suggested, the machine will immediately operate automatically to remove the record on the platen and substitute another record for it.

A further object of the invention is to provide simple means for controlling the machine, and also to provide simple means for effecting the return of the magazine to its normal position after the machine has operated to play all the records.

A further object of the invention is to provide simple means for preventing the returning movement of the magazine from occurring unless the parts of the machine are in proper position to permit such a movement of the magazine.

Further objects of the invention will appear hereinafter.

The invention consists in the novel parts and combination of parts to be described hereinafter, all of which contribute to produce an efficient multiple record playing phonograph.

A preferred embodiment of the invention is described in the following specification

while the broad scope of the invention is pointed out in the appended claims.

In the drawing:

Figure 1 is a front elevation of a machine embodying my invention. 60

Fig. 2 is a side elevation of the machine shown in Figure 1.

Fig. 3 is a vertical section through the machine. 65

Fig. 4 is a plan with certain parts broken away and shown in section.

Fig. 5 is a view similar to Figure 4 but with certain parts broken away and shown in section, particularly illustrating the stop device for controlling the automatic operation of the mechanism, and also illustrating the means for insuring continuous automatic operation of the machine in case a record is omitted from its place in the stack of records 70 75

in the magazine.

Fig. 6 is a horizontal cross section taken

about at the level of the line 9—9, of Figure 3 and looking downwardly.

Fig. 7 is a side elevation partially broken 80 away so as to show a portion of the interior as though taken in section at about the location of the line 7—7 of Figure 6.

Fig. 8 is a vertical section taken about at the location of the line 8—8 of Figure 4. 85

Fig. 9 is a cross-section taken at about the level of the line 9—9 of Figure 3, but looking upwardly.

Fig. 10 is an elevation of the machine as viewed from the right side of Figure 6, partially broken away so as to show the wall in section and the inner mechanism in elevation. 90

Fig. 11 is a front elevation broken away and showing some of the parts in cross section. 95

Fig. 12 is a fragmentary view, being an elevation and further illustrating details of the mechanism and showing the effects of a possible extra movement of the hand operated stop-lever and the mechanism which closes the gates between the magazine and the platen. 100

Before proceeding to a detailed description of the machine it will facilitate the disclosure to state that the invention involves the use of a rotary platen for holding the record which is being played and includes automatic mechanism for changing the record. In order to accomplish this a stack of records is provided, and the mechanism operates to take a record from the stack or a magazine and place it on the platen after 105 110 115

having first removed the record which has just been played. In the normal operation of the machine, after a record has been played, the needle is automatically lifted from the record and the needle arm is automatically returned to its starting position, whereupon the record on the platen is removed from it and the new or substituted record placed on the platen; as soon as this operation takes place the machine operates automatically to set the needle in contact with the new record. Any suitable means may be provided for holding the records and enabling them to cooperate with the record-changing mechanism. However, the machine as described embodies a magazine which carries the records in separate pockets, and in the automatic operation of the machine the magazine is advanced by a step by step movement so as to bring the different pockets in succession into alignment with the platen; when the automatic playing mechanism cooperates with such a magazine, the played record is automatically returned to its pocket in the magazine and the magazine then advances automatically and is held in position to enable the next record to be taken from it by the automatic mechanism and placed on the platen.

The machine also includes a hand operated member, for example, a lever, which when operated immediately stops the playing of any record which happens to be on the platen and brings into operation the regular automatic mechanism which immediately operates to effect the change of the record as though the machine had completed the playing of the record then on the platen.

Suitable means is provided to enable this same hand-operated member to have an extra movement, the function of which is to effect the return of the magazine to its normal position, but the mechanism is so constructed that this extra movement of the lever cannot occur unless the mechanism is held so that all its parts will clear the magazine; this prevents any possibility of the movement of the magazine jamming any of the parts of the mechanism; and I provide automatic means for locking or latching the mechanism in the proper position to permit the movement of the magazine when such a movement is desired.

I shall now proceed to a more detailed description of the mechanism. The machine comprises a cabinet or casing 1 which may be of box form as shown in Figures 1 and 2 and provided with double doors 2, and double doors 3, the former of which render the magazine of the machine accessible from the exterior, and the latter of which cover the outer end of the horn or sound duct 4 of the instrument, see Figure 3.

In the upper portion of the interior of the cabinet, a horizontal frame plate 5 is

provided, see Figure 8, which supports a rotatable platen 6, which is preferably continuously driven, for which purpose the platen is supported on a tubular spindle 7, the lower portion of which carries a gear wheel 8 driven by another gear wheel 9 which meshes with it. This gear wheel 9 is carried on a vertical shaft 10 supported in the frame 11 of the instrument and continuously driven through beveled gears 12, 75 one of which is carried on a horizontal shaft 13 driven by a belt from a motor 14. This motor is preferably a small electric motor, but if desired a spring motor may be used.

Near one edge of the platen, see Figure 8, 80 a vertical partition wall 15 is provided, the lower edge of which is disposed above the level of the platen 6 so as to form an opening or gap 16 through which the records may be slid out onto the upper face of the platen. 85 The records are received in the space above the platen and beneath a guide plate 17, which is cut away so as to form a gap or opening 18, see Figure 4. This gap or opening 18 is provided to permit operation of the 90 needle arm 19 and needle 20 carried thereby. The needle 20 is supported adjacent to a sound box 21 of ordinary construction carried on the outer portion 19^a of the arm, which connects with the body of the arm by 95 a pivot joint 22 of any common construction, which will permit the needle to be let down onto the record on the platen.

The needle arm 19 rotates on a vertical axis, that is to say, it is swiveled on a vertical axis on a base 23 supported on the horizontal frame plate 5.

The mechanism is preferably constructed so that as soon as the playing of the record is ended, the movement of the needle arm at the end of its travel activates or actuates the automatic mechanism which then performs the cycle of operations necessary to effect the changing of the record, leaving the mechanism again in the same relation which it had when the playing of the record commenced. In order to accomplish this, I prefer to employ a counter shaft 24 which is normally held in a stationary position by a stop device 25, see Figure 5. This stop device includes a slide 26 guided on the upper face of the frame plate 5 by means of screws 27 running in a slot 28, and the outer end of this slide is connected by a connecting rod 29 with a rigid arm 30 which extends 105 radially from the needle arm, see Figure 4. The outer end of this stop or slide 26 normally is disposed in the path of a small arm 31 which is secured by a set screw to the counter shaft. When the playing of a record 110 is completed the arm 30 withdraws the stop 26 and permits one rotation of the shaft 24; that is to say, before the shaft 24 can make more than one revolution the stop 26 is projected back into the path of the arm 31. 115 120 125 130

A starting device is provided for the counter shaft consisting of a cam 24^a (see Fig. 5). In the position of rest this cam is pressed by a leaf spring 24^b, and the toe of the cam is just beyond dead center so that the force of the leaf spring is exerted in a direction to start the rotation of the counter shaft as soon as it is released.

The first movement of the counter shaft 10 24 performs the function of lifting the needle off of the record and any other function which is necessary to prepare the platen to have the played record removed from it. As usually constructed every platen has a 15 center pin which is received in an opening in the record. In order to adapt my machine to properly center the records and to enable it to play records as usually constructed, I provide the platen with a longitudinally 20 movable sliding pin 32.

In order to lift the needle off the record, I provide a guide or guide bar 33, see Figure 8, one end of which is pivotally supported on the wall 15, and the other end of which 25 has a pin-and-slot connection with a vertically sliding post 34, which is guided to slide through the frame plate 5. The sound box 21 of the instrument is provided with a horizontal finger 35 which projects out over 30 the upper edge of the guide 33, its movement being limited by two stops 36 and 37, which are formed on the upper edge of this bar. The first movement of the shaft 24 operates to engage the teeth of a mutilated gear 24^c 35 (carried on shaft 24) with the teeth of the pinion 13^a. The countershaft is then driven and immediately withdraws the sliding pin 32 and moves up the post 34, whereupon the guide bar 33 engaging the finger 35 lifts the 40 needle off the record. The post is held in its raised position by an automatic latch to be described hereinafter. This movement of the post and sliding pin may be accomplished by means of a cam 38 which engages 45 a short arm 39 extending up from a rock shaft 40, said rock shaft carrying a lever, one arm 41 of which has a pin-and-slot connection with the lower end of the post 34, and the other arm 42 is formed into a yoke 50 with a pin-and-slot connection with a swivel 55 head 43 on the lower end of the sliding pin 32, which rotates with the platen. A helical spring 44 which is attached to the arm 41, holds the arm 39 up against the cam and exerts its force in a direction to hold the post 34 in its depressed position.

The stop device 25 operates as means for effecting the connection between the counter shaft and the continuously driven shaft 13. 60 To do this the shaft 13 carries a pinion 13^a that meshes with the mutilated bevel gear 24^c. That is to say the gear 24^c has a gap in its teeth that lies opposite the pinion when the counter shaft is at rest.

65 In the operation of the machine, as soon

as the needle has been lifted off of the record and the center pin 32 withdrawn, the other parts of the record changing mechanism operate automatically to move the played record off the platen and to substitute a new 70 record. In order to accomplish this, in a machine having a magazine such as suggested, I construct the machine with a magazine 45 guided to move up and down in the cabinet, and having a plurality of pockets 46 75 to receive the records. By suitable mechanism, to be described hereinafter, this magazine is advanced by a step by step movement so as to bring the different pockets successively to the level of the platen. As illustrated in Figure 8, the magazine is shown in its raised, or starting, position, but without any records in it.

It should be understood that, at the moment of the completion of playing a record 80 on the platen, the empty pocket of the magazine from which the record was taken will be held at the level of the platen ready to receive again the record which it formerly contained.

The gap 16 between the magazine and the platen is provided with a sliding gate 47, see Figure 8, which is normally open.

In order to remove the record on the platen, I provide ejector means preferably 90 in the form of a curved ejector arm 50, see Figure 4, which is secured rigidly to a vertical ejector shaft 51, see Figures 4 and 6. This ejector shaft is provided with a rigid arm 52 to which is attached a connecting rod 53, one end of which has an adjustable pin-and-slot connection 54 with an actuating lever 55, said lever being mounted to rock on a fulcrum pin 56 and having two forks forming a yoke 57 which cooperates 100 with a cam 58 carried on the aforesaid counter shaft 24 (see Fig. 6). When the counter shaft 24 is released and makes its single revolution which puts the mechanism through the cycle of movements necessary 105 to change the record, the shaft 24 rotates in a right-hand direction, as indicated by the arrow in Figure 6. This actuates lever 55, link 53, arm 52, and produces a turning movement of the ejector shaft 51 also in a 110 right hand direction and this brings the ejector arm 50 into contact with the edge of the record and starts to slide the record off of the platen into its pocket in the magazine. During this ejecting movement of the 115 arm 50 the needle arm 19 is automatically returned to the starting position.

In order to accomplish this the ejector shaft 51 is provided with a rigid arm 59, the outer end of which is pivoted to a thrust bar 60 having a longitudinal slot 61 in which travels a small post or finger 62 which extends down from the needle arm, see Figure 3. The thrust bar is supported on an adjustable collar in the form of a nut 62^a threaded on 120

90

100

105

110

115

120

125

130

the post 62. When the ejector arm 50 performs its swing to the right to eject a record from the platen, the inner end of this slot 61 engages the post 62 and pushes the needle 5 arm 19 outwardly, that is to say, it rotates it in a left hand direction and brings the stop finger 35 substantially against the outer stop 36 on the guide bar 33, see Figures 4 and 8. The movement of the ejector arm 10 50 is sufficient to move the record completely through the gap 16, see Figure 4, and past the position of the gate 47, see Fig. 8. As the played record advances, the curved injector arm 63, see Figure 9, withdraws from 15 the pocket in the magazine which lies opposite to the platen and swings way over to the right out of the path of the magazine so as to permit a feeding movement of the magazine to bring the next record into alignment with the platen. In order to accomplish this the injector arm 63 is carried upon a vertical injector shaft 64, see Figure 4, and this shaft is provided with a rigid arm 65, see Figure 6, which is somewhat similar 20 to the arm 52 on the ejector shaft 51. This arm 65 is engaged by a pin 66 which projects down from a slide bar 67 connected to the arm 52 by a link 68 and mounted to slide in suitable guides 69 and 70. When the 25 slide bar 67 shifts to the right to its full movement, the pin 66 will hold the arm 63 in an extreme position at the right where it will be out of the path of the curved edge 71 of the magazine, see Figure 9. With the 30 injector arm 63 in this position, the magazine 45 is then automatically moved so that it will descend through the height of one pocket and bring the next pocket into line with the platen. This movement of the 35 magazine is accomplished by guiding it in a vertical direction and partially counter balancing it, and also by controlling an escapement device connected with the magazine, through the agency of the slide bar 67. For 40 this purpose the magazine is provided with a central tubular shaft 72, see Figure 8, which telescopes over a fixed post 73 in the bottom of the cabinet, a helical spring 74 being provided on the top of the post 73 which 45 thrusts against the bottom of the magazine. This spring is not quite strong enough to 50 support the weight of the magazine and hence when the escapement referred to above is actuated, it will permit the magazine to 55 descend. As suggested, I provide an escapement device 75, see Figure 6, which cooperates with a horizontal shaft 76 carrying a pinion 77 which meshes with a rack 78 which is connected with the magazine so that the 60 rack moves when the magazine moves. For convenience this rack may be formed directly on the side of the tubular shaft 72, see Figure 8. The escapement device 75 comprises a double pawl 79, see Figure 7, consisting of two oppositely disposed dogs 80, 65 and when the machine is at rest the right hand dog 80 is held against movement by one arm of a yoke 81 which constitutes part of the escapement device, the said yoke being mounted on a pivot 82 and pulled by a 70 spring 83 in a direction to hold the right hand fork of the yoke under the right hand dog. At the last part of the movement of the slide bar 67, this yoke 81 is actuated. For this purpose an escapement device is 75 provided, that is to say, the slide bar 67 has a laterally projecting rigid arm 84, see Figure 6, which carries a pin running in a slot 85 on the end of a drag link 86. As soon as this pin arrives at the end of the slot 80 85 it shifts the yoke 81 to the right and lets the shaft 76 make one half-revolution. But it will permit only one half-revolution because the spring 83 operates (as the bar 67 moves back to its normal position) to pull 85 the yoke back so that its right hand fork comes under the approaching dog 80. In connection with the operation of this part of the mechanism it should be understood that the movement of the injector arm 63 90 which occurs simultaneously with the operation of this mechanism, is sufficient to enable this arm 63 to travel a slight distance beyond the point which it must reach in order to clear the magazine. After the 95 arm 63 has completed this movement it is pulled back toward its normal position by a coil spring 87, see Figure 7, one end of which is attached to a collar on the slide bar 67 and the right hand end of which is attached to 100 the arm 65 on the injector shaft 64. However, before the arm 63 returns from the slight extra movement or excess movement which is necessary to permit the magazine to have this movement, the magazine will have 105 advanced so that the next pocket 46 above the played record will be at the level of the arm 63, and hence when the arm 63 is completing its return movement by the spring 87, it will enter the pocket carrying the next 110 record which is to be played and will push the record through the gap 16 onto the platen 6. While this is occurring the sliding pin 82 is held withdrawn; the movement of the record onto the platen is therefore unobstructed. When the record comes onto the platen in this way, it will be remembered the post 34 is already latched in an elevated position by means of a small latch; this latch 88, (see Figure 4,) is in the form 115 of a pawl to engage under a rounded shoulder 89 on the adjacent side of the post, said pawl being mounted to rock on a vertical pin 90; automatic means is provided to release the latch; in the present embodiment this means is in the form of a curved arm or tail 91 rigid with the latch and which is engaged by the incoming record as it arrives at its central position. In other words, 120 as the record comes into place it swings the 125 65

pawl against the action of its spring 92, see Figure 4 and rocks the pawl in a left hand direction. This releases the post 34 which is immediately pulled down by its spring 44. 5 This movement of the post lets down the guide bar 33 and sets the needle 20 on the upper face of the new record to permit it to be played. When the post 34 drops, the rounded shoulder shoves out the pawl and 10 the side of the post holds the curved tail 91 out of contact with the record. This movement of the post also slides up the center pin 32 to its normal position.

The mechanism above described will operate to play all the records in the magazine in succession, effecting the automatic changing of each record after it has been played. However, I provide the mechanism with means for stopping the playing of 15 a record at any point desired, and when this means is operated the machine automatically effects the changing of the record. In order to accomplish this, I provide a hand operated member which is preferably 20 in the form of a stop lever 93, see Figure 6, the outer end of which projects through a slot 94 in the forward wall of the cabinet. The first part of the movement of this lever operates to lift the needle off the 25 record. In order to accomplish this, I provide a lever 95, see Figure 11, having its fulcrum at 96 and normally disposed in an inclined position so that it will be forced down by the movement of the lever 93 which 30 will be toward the right, as viewed in Figure 11. The outer end of this lever 95 is connected by a link 97 with an arm 98 forming part of a bell crank lever 99, the other arm 100 of which engages a pin 101 projecting from the lower end of the post 34. With this organization of parts it will 35 be evident that a movement of the lever 93 toward the right will shove the post 34 upwardly. As soon as the post is moved upwardly sufficiently, the spring 92 of the latch 88 will cause the latch to hold the post in its elevated position. This movement lifts the needle off the record and lowers the pin 32. The further movement of 40 the lever 93 operates a member in the form of a trigger 102, see Figure 11, and this trigger is connected with the needle arm so as to swing the needle arm over to the end of its travel. The construction is such that 45 the lever 93 will operate the trigger 102 and then release it. For this purpose the trigger 102 is mounted on a pivot 103 on a bracket 104 and the trigger is normally held in a vertical position by a helical spring 105. Above the pivot 103 the trigger has attached to it a link 106 which has a pin-and-slot connection 107 with a vertical arm 108 which extends up from a horizontal rock shaft 109, see Figures 6, 7 and 50 11. This rock shaft is supported near the

bottom of the cabinet on suitable brackets 110 and its other end is provided with a downwardly projecting inclined arm 111 which is connected to an inclined link 112 which extends upwardly so that its upper 70 end extends through an opening 113, see Figure 5, formed in the aforesaid frame plate 5. The upper end of this link is attached to an arm 114 carried on a horizontal rock shaft 115, the other end of said 75 rock shaft having an arm 116 which is connected by a link 117, and spring 118, with the needle arm 19. It will be evident that when the stop lever actuates the trigger 102, the inclined link 112 will operate to swing 80 the needle arm over to the end of its travel as if it had been moved there through the playing of the record. If the stop lever is immediately returned to its normal position, the operation of the machine will be regular, that is to say, it will automatically effect the changing of the record. I utilize this same stop lever 93 to effect the return of the magazine to its normal position after all the records have been played. This 85 is accomplished by giving the stop lever 93 an extra movement. However, in order to prevent this magazine-returning mechanism from being brought into action when it is not intended to have it operate, I provide an automatic stop in the path of the lever 93 which prevents this extra movement from occurring, normally. In Figure 90 11, 119 represents this automatic stop which is in the form of a bell crank lever having 95 a horizontal arm, the end of which is engaged by the lever 93 in the normal operation of the machine. If the record on the platen is the last record to be played, the operator does not return the lever 93 to its 100 normal position, but holds it lightly against the stop 119. I provide automatic means operating under these circumstances to latch the injector arm 63 when it is in its extreme right hand position, that is to say, 105 when it is out of the path of movement of the magazine; Figure 4 shows this arm 63 but not in the withdrawn position referred to. By latching this arm in its withdrawn position, and withdrawing the automatic 110 stop 119 automatically from the path of the lever 93, the lever 93 may then be given a further movement which connects the motor of the instrument to the magazine to raise the magazine to its normal position. 115 In order to accomplish this, I provide a latch bar 120, see Figure 10, which is pivotally supported at 121, and extends across so that its outer end lies near the path of movement of arm 65. A coil spring 122 tends to pull this latch bar 120 upwardly, 120 but the latch bar is normally held down so that it will not operate as a latch, by a detent arm projecting across its upper edge. This detent arm 123 is connected by a link 130

124 with the stop lever 93. When the stop lever 93 is moved from the position shown in Fig. 11 over against the automatic stop 119, the link 124 will move the detent 123 by 5 rocking it on its pivot 125, and this will permit the spring 122 to pull the latch bar 120 up into the path of the arm 65. Now, if the stop lever 93 is immediately returned to its normal position, the latch bar 120 will 10 not operate, but if it is held against the automatic stop 119, the automatic mechanism of the machine will operate to remove the record on the platen and as soon as it is removed the bar 120 will swing up into the 15 path of arm 65; this will keep the injector shaft from rotating back, and will latch the injector arm 63 in position to clear the magazine when it moves. In other words, if the stop lever is left in this position, the 20 machine will set itself automatically in readiness to permit the return of the magazine. Furthermore, if the lever is left in this position, the automatic stop 119 will be automatically withdrawn to permit this 25 necessary extra movement of the lever to effect the return of the magazine to its normal position. In order to withdraw the 30 automatic stop, I provide a lever 127, see Figure 6, one end of which projects into the path of the end of the slide bar 67 and adjacent the guide 70, see Figures 6 and 7. The other end of this lever 127 is connected to the vertical arm of the stop by a link 128. This will pull the automatic stop up out 35 of the path of the lever 93, see Figure 12. The further movement of this lever permitted by the removal of the automatic stop closes a clutch 129, see Figure 6, the movable clutch member 130 being operated by a link 131 having a slot 132 to receive a 40 pin 133 on the lever 93. In the operation of the lever, as illustrated in Figure 6, when the pin 133 strikes the end of the slot 132, its further movement will close the clutch. 45 The movable clutch member 130 is splined on a horizontal shaft 134 carrying a pinion 135 meshing with a gear wheel 136 carried on the aforesaid shaft 76 which carries the pinion 77. Hence by rotating this shaft 76, 50 the pinion 77 will operate on the rack 78 to raise the magazine and return it to its normal position.

I provide means for closing the gate 47 when the magazine 45 is being returned in 55 order to prevent any possibility of the edges of the records from getting caught at the lower edge of the wall 15 and in the gap 16. In order to accomplish this, the gate 47 is connected by a link 137 with a horizontal arm of a bell crank lever 138, the vertical arm of which is adapted to be struck by the lever 93, see Figure 12, when the lever 93 is given this extra movement which may be permitted by the automatic 60 stop 119. Figure 12 shows the automatic

stop raised out of the way so as to permit the lever 93 to pass it when this lever is used to close the clutch 129 and return the magazine to its raised position. In the use of a machine of this type having a magazine 70 it might happen that one or more of the pockets 46 of the magazine might be left empty. I provide for this contingency and construct the automatic mechanism in such a way that if the magazine has an 75 empty pocket, it will not interfere with the automatic operation of the machine. In other words, if there is an empty pocket the mechanism will operate to give the magazine another advancing movement so as to 80 bring the next pocket carrying a record, to the level of the platen. In order to accomplish this, I provide means corresponding to each pocket and controlled by the record within the pocket in such a way that if the 85 record is not in the pocket, this means will function to throw the automatic mechanism immediately into operation to give the magazine its feeding movement. For this purpose I simply provide each pocket with a 90 trip device in the form of a dog 139, see Figures 4 and 5. This dog is pivoted at 140 and has a small arm or tail 141 which is engaged by the record 142, see Figure 4, when the record is in place, so as to extend 95 the spring 143 on the dog. Figure 4 shows the dog held in its inoperative position. However, when the record is absent from the pocket, this dog 139 is in a projecting position, that is to say, it projects over so 100 that a member such as the pawl 144 lies in its path of movement. This pawl is pivoted on a suitable bracket 145 in a pocket or recess 146 in the side of the cabinet and when an empty pocket arrives opposite the 105 pawl, the dog 139 corresponding to that pocket projects out over the arm of pawl 144, so that when the magazine descends, it actuates the pawl. I utilize the movement 110 of this pawl to swing the needle arm 19 to its final position, that is to say, to the end of its travel. The arrival of the needle arm at the end of its travel, of course, operates the automatic mechanism to actuate the feeding mechanism for the magazine. Incidentally the record-changing mechanism 115 will go through the movements of exchanging the record although the played record will already have been removed from the platen.

In order to enable the pawl 144 to actuate the needle arm in the manner described, one arm of the pawl is attached to a link 147 which extends downwardly, its lower end being secured to an arm 148 carried by the 125 aforesaid rock shaft 109, see Figures 6 and 7. The direction of movement of the link 147 will be upward so that the rotation of the rock shaft 109 will produce a pull in the link 112, already described.

The pin-and-slot connection, already described, in the link 106, will permit the return of trigger 102 to its vertical position while leaving the needle arm in the position 5 that it may be moved to by the lever 93 in stopping the playing of a record.

The general mode of operation of the machine will now be briefly described. The record on the platen 6 is played in the ordinary way, that is to say, the needle starts at the outer edge of the record and moves inwardly toward the center. When the needle arm 19 arrives at the end of its travel, the arm 30 pulls on the link 29 and operates 10 the stop device 25; this removes the slide 26 from in front of the arm 31, see Figure 5. As soon as this occurs, the leaf spring 24^b exerting its force against the toe of the cam 24^a initiates a right-hand rotation of the 15 counter shaft 24. The movement given to the shaft by this spring 24^b is sufficient to cause engagement of the teeth of the mutilated gear 24^c with the continuously driven pinion 13^a. This pinion 13^a rotates the shaft 24 in the same direction in which it was 20 started by the spring 24^b. Through the action of the cam 38 on the arm 39, the lever arm 41, see Figure 8, shoves up the sliding post 34 whereupon the latch 88 (see Fig. 4) 25 latches this post in an elevated position. This movement raises the bar 33 and through the agency of the finger 35 raises the needle off the record. While the sliding post 34 is 30 being raised in this way, the sliding pin 32 is being withdrawn by its actuating arm 42. There is then no obstruction to prevent the removal of the record which has just been played. This is accomplished immediately by the cam 58, operating lever 55 and link 35, see Figure 6, which is attached to the arm 52 on the ejector shaft 51. This swings the 35 ejector arm 50 around so that it slides the record off of the platen and into its corresponding pocket 46 where it belongs. As the 40 ejector arm 50 swings around, see Figure 4, the arm 59 through the agency of the slot 61 and bar 60, engaging the post 62, swings the needle arm 19 outwardly to its starting 45 position in which it is shown in Figure 4.

As the played record moves over into its magazine pocket 46, the injector arm 63, see 50 Figure 4, swings out of the pocket into which the record is advancing; this injector arm is 55 swung back by means of the pin 66, see Figure 6, operating upon the arm 65 carried by the injector shaft 64. This swings the arm 63 away back out of the path of the magazine 60, that is to say, it moves beyond the curved edge 71 of the magazine. As soon as the injector arm 63 has moved clear of the magazine, then the arm 84, see Figure 6, actuates the link 86 to rock the escapement yoke 81, thereby permitting one half-revolution of the 65 shaft 76 and operating through the pinion 77 and rack 78, see Figure 8, to permit the

descent of the magazine until the next pocket 46 above, has come into line with the platen; in other words the double dog pawl 79 cooperates with the yoke to effect a single half-revolution of the shaft 76 so that the escapement yoke 81 holds the magazine in its new feeding position. As soon as the magazine has accomplished this feeding movement, the injector arm 63 commences its swing toward the left and engages the record 70 142 in this pocket, and slides it out onto the upper face of the platen. As the record comes over to its proper position the forward edge of the record engages the pawl 91 of the latching pawl 88, see Figure 4, and 75 this releases the sliding post 34 from this latch and lets the needle 20 down onto the record. The movement of this post, of course, operates through the arm 41, and the arm 42 to slide the pin 32 up into the central 80 opening of the record. The sliding pin then exactly centers the record on the platen, and the playing of the record will begin at once. The above operation constitutes substantially one complete cycle in the normal 85 operation of the machine.

I shall now describe an abnormal operation which will occur if the operator of the instrument desires to stop the playing of a record after it has begun or at any time before the playing of the record has been completed. In order to do this the operator simply moves the lever 93, see Figure 6. He moves this lever as far to the right as it will go, see Figure 11, which will bring 90 the lever up against the automatic stop 113 which will prevent further movement of the lever. As the lever begins its movement toward the right, see Figure 11, it operates the lever 95 and this actuates the link 97 95 and arm 100 which raises the sliding post 34; as soon as the sliding post 34 has been lifted sufficiently, it will be automatically latched in its raised position by the automatic latch 88. This removes the needle 100 from the record in the same manner as occurs in the normal operation of the machine. Immediately after this has occurred, the lever 93 strikes the trigger 102, see Figure 11, and this actuates the link 106 and rocks the 105 rock shaft 109, thereby producing a pull on the inclined link 112, see Figure 7, and this operates the rock shaft 115, see Figure 4 and produces a pull in the link 117 exerted through spring 118; this pulls the 110 needle arm 19 over so as to bring the finger 35 against the right hand stop 37; in other words it moves the needle arm over to the end of its travel. The movement of the needle arm to this position through the operation of the arm 30 produces all the regular automatic movements of the record changing mechanism so that the ejector arm 115 120 125 50 is then actuated to shove the record off the platen, and into the magazine. If the 130

lever 93 is then returned to its normal position, it rides back over the trigger 102, as will be permitted by the spring 105; this return movement of the lever is facilitated 5 by the beveled upper end of the trigger 102. If the record which has just been played is the last record in the magazine, the operator would not return the lever 93, but should leave it pressed lightly against the stop 119. 10 The machine will then operate the record-changing mechanism, but instead of effecting the return movement of the injector arm 63, this arm will be locked in its extreme position toward the right and out of the 15 path of movement of the magazine 45, see Figure 4. This is accomplished through the agency of the detent pawl 123, see Figure 3, which operates when it is raised through the agency of link 124, to permit the latch bar 20 120 to swing upwardly under the action of its spring 122 so as to project its free end into the path of the arm 65 which will then be in an extreme right hand position to correspond with that position of the injector 25 arm 63. This holds the injector arm in the proper position to permit the magazine to be returned by power to its normal raised position. Furthermore the automatic stop 119 will now have been automatically with- 30 drawn from the path of the lever 93, and permits the extra movement of this lever which will close the clutch 129. The withdrawal of the automatic stop 119 is accomplished by the end of the shifting bar 67, 35 see Figure 6, which actuates a lever 127 which is connected by a thrust link 128 with the vertical arm of the automatic stop, see Figure 11. When the clutch 129 is closed by this extra movement of the lever 93, the 40 continuously driven shaft 13 operates to rotate the pinion 77 in a direction to move the rack 78 upwardly, thereby raising the tubular shaft 72, and the magazine 45 attached to its upper end. 45 This extra movement of the lever 93 also, see Figure 12, operates through the bell crank 138 and the link 137 to close the gate 47 so that while the magazine is returning 50 none of the records can become caught in the gap 16.

The inclined or curved rear edges of the dogs 80 of the double pawl 79 permit the rotation of the shaft 76 as the magazine is being lifted. These curved edges simply 55 engage the forks of the yoke 81 and swing the yoke back and forth as the shaft 76 revolves.

It is understood that the embodiment of the invention described herein is only one of 60 the many embodiments this invention may take and I do not wish to be limited in the practice of my invention nor in my claims to the particular embodiment set forth.

What I claim is:

65 1. In a machine of the kind described,

the combination of a continuously-driven platen for receiving the record that is to be played, a pivoted arm carrying a sound box and needle to cooperate with the record, and automatic means controlled by the needle-arm at the end of its travel in playing the record, for changing the record. 70

2. In a machine of the kind described, the combination of a rotatable platen having a longitudinally movable center-pin guided to withdraw downwardly through the table, 75 a motor for rotating the platen, automatic means for withdrawing the center-pin from the record after the same has been played, and automatic means for changing the record and returning the center-pin. 80

3. In a machine of the kind described, the combination of a rotatable platen having a longitudinally movable center-pin guided to withdraw downwardly through the table, 85 means for rotating the platen, a magazine having a plurality of pockets for records, means for guiding the magazine and for holding the same successively in positions to align the different pockets with the platen, 90 a needle arm to cooperate with the record being played, and automatic means controlled by the needle-arm at the end of its travel in playing a record, for withdrawing the center-pin downwardly and for effecting the removal of the played record thereafter to one of the said pockets of the magazine, 95 and for advancing the magazine to align the next record with the platen, and for advancing the said next record onto the platen. 100

4. In a machine of the kind described, the combination of a rotatable platen having a longitudinally movable center pin, a motor for rotating the platen, a magazine having a plurality of pockets for records, means for guiding the magazine and holding the same successively in positions to align the different pockets with the platen, a needle arm and needle to cooperate with the record being played, a movable gate between the magazine and the platen, automatic means controlled by the needle arm at the end of its travel in playing a record, for effecting the removal of the played record, for advancing the magazine to align the next record 115 with the platen and for advancing the said next record onto the platen, a clutch for connecting the motor to the magazine for returning the magazine after all the records have been played, a lever, means actuated thereby for closing said gate, and means actuated by said lever for closing said clutch to effect the return of the magazine. 120

5. In a machine of the kind described, the combination of a rotatable platen to receive 125 a record to be played, a pivoted needle arm carrying a sound box and needle, automatic means for removing the record after it has been played and for substituting another record therefor, a manually operated member 130

for stopping the playing of the record, and means connecting the manually operated member to the needle arm to return it to its starting position said automatic means operating thereafter to effect the changing of a record.

6. In a machine of the kind described, the combination of a rotatable platen to receive a record to be played, a movable needle-arm and needle to cooperate with the record, automatic mechanism controlled and brought into operation by the needle-arm when it reaches the end of its travel in playing a record, and operating to remove the played record and substitute another record therefor, a manually operated member operable at any time during the playing of a record, and means actuated thereby for displacing the needle from the record and moving the needle arm to the end of its travel whereby the needle-arm automatically effects the changing of the record.

7. In a machine of the kind described, the combination of a rotatable platen, a motor for rotating the same, a pivoted needle-arm and needle to cooperate with the record on the platen, and automatic means actuated by the needle-arm at the end of its travel for effecting the lifting of the needle off the record and for changing the record.

8. In a machine of the kind described, the combination of a rotatable platen having a longitudinally movable center-pin, a motor for driving the platen, a pivoted needle-arm having a needle to cooperate with a record on the platen, a magazine for records, and automatic means controlled by the needle-arm at the end of its travel for withdrawing the center-pin and cooperating with the magazine to change the record.

9. In a machine of the kind described, the combination of a rotatable platen to receive a record to be played and having a longitudinally movable center-pin, a motor for driving the platen, a pivoted needle-arm carrying a needle to cooperate with the record, a movable guide-bar for the needle-arm and capable of lifting the needle out of contact with the record, a magazine for holding a plurality of records, and automatic means controlled by the needle-arm at the end of its travel for withdrawing the center-pin, and operating to remove the record on the platen to the magazine, and advance the next record from the magazine onto the platen, and also operating to return the center-pin to its normal position, return the needle-arm to its starting point, and for controlling the guide-bar to permit 60 the needle to engage the new record.

10. In a machine of the kind described, the combination of a rotatable platen to receive a record to be played, a motor for rotating the platen, a needle-arm and needle 65 to cooperate with the record on the platen,

a continuously driven shaft, a counter-shaft having a normally disconnected driving connection with the driving shaft, means actuated by the needle-arm at the end of its travel for effecting the connection of the counter-shaft to the continuously driven shaft, means actuated by the counter-shaft for lifting the needle out of contact with the record, and automatic means for effecting the changing of the record.

11. In a machine of the kind described, the combination of a rotatable platen to receive a record to be played, and having a longitudinally movable center-pin, a motor for rotating the platen, a continuously driven shaft, a normally stationary counter-shaft, a pivotally-mounted needle-arm having a needle to cooperate with the records, a stop-device controlled by the needle-arm and normally holding the counter-shaft against rotation, automatic means to effect the connection of the counter-shaft to the driven shaft when the stop-device is actuated, means actuated by the counter-shaft to withdraw the center-pin, and automatic means 90 for effecting the change of the record thereafter.

12. In a machine of the kind described, the combination of a rotatable platen to receive a record to be played, a motor for 95 rotating the platen, a needle-arm and needle to cooperate with the record on the platen, a continuously-driven shaft, a counter-shaft having a mutilated gear, a pinion carried by the said continuously-driven shaft and capable of meshing with the mutilated gear to drive the counter-shaft, means for normally holding the counter-shaft in a position to maintain the mutilated point of the mutilated gear opposite the pinion so that 100 the drive to the counter-shaft is normally disconnected, means controlled by the needle arm at the end of its travel for effecting a slight rotary movement of the counter-shaft to bring the teeth of the mutilated 105 gear into mesh with the pinion, and means actuated by the counter-shaft to effect the changing of the record.

13. In a machine of the kind described, the combination of a rotatable platen to receive a record to be played, a motor for rotating the platen, a needle arm and a needle to cooperate with the record on the platen, a continuously-driven shaft, a counter-shaft normally stationary, said counter-shaft and said continuously-driven shaft having a mutilated gear connection whereby a slight rotation of the counter-shaft will connect the same to the continuously-driven shaft, a stop controlled by the needle arm 115 for normally holding the counter-shaft against rotation, means for producing a slight rotation of the counter-shaft when the stop is withdrawn to effect the meshing 120 of the mutilated gears, and automatic means 125 of the mutilated gears, and automatic means 130

for changing the record actuated through the counter-shaft.

14. In a machine of the kind described, the combination of a rotatable platen to receive a record to be played and having a longitudinally sliding center pin, a motor for rotating the platen, a needle arm and needle to cooperate with the record on the platen, an actuating lever connected at one end with the center pin and having means connected with its other end for lifting the needle out of contact with the record, automatic means for actuating said lever at the end of the travel of the needle arm, and automatic means for effecting the changing of the record.

15. In a machine of the kind described, the combination of a rotatable platen to receive a record to be played and having a longitudinally sliding center pin, a motor for rotating the platen, a needle arm and needle to cooperate with the record on the platen, an actuating lever connected at one end with the center pin and having means connected with its other end for lifting the needle out of contact with the record, an automatic latch for latching the needle arm in an elevated position with the needle out of contact with the record, automatic means for actuating said actuating lever at the end of the travel of the needle arm to effect the lifting of the needle arm and the withdrawal of the center pin, automatic means for effecting the changing of the record, and automatic means for returning the needle arm to its starting position, said latch having a part projecting into the path of the new record as it comes into place on the platen to enable the new record to release the latch and permit the needle to descend onto the face of the new record.

16. In a machine of the kind described, the combination of a rotatable platen to receive a record to be played, a needle arm and needle to cooperate with the record on the platen, a guide for the needle-arm, a sliding post connected with the guide and capable of actuating the guide to lift the needle arm to remove the needle from the record, and to permit the needle to descend upon the record, means for actuating the sliding post at the end of the travel of the needle-arm to lift the needle-arm away from the record, a latch cooperating with the sliding post to hold the said guide elevated with the needle out of contact with the record, automatic means for effecting the changing of the record, automatic means for returning the needle arm to its starting position, and automatic means for releasing the latch to let down the needle arm to engage the needle with the face of the new record.

17. In a machine of the kind described, the combination of a rotatable platen to receive a record to be played, a needle-arm

and needle to cooperate with the record on the platen, record changing mechanism including automatic means for removing the record after it has been played and for substituting another record therefor controlled by the needle arm at the end of its travel, a manually operated member for stopping the playing of the record, and means connecting the same with the needle and operating to move the needle arm over to the end of its travel, whereby the record changing mechanism operates automatically thereafter to effect the changing of the record.

18. In a machine of the kind described, the combination of a rotatable platen to receive a record to be played, a needle arm and needle to cooperate with the record on the platen, a manually operated member, means actuated thereby to lift the needle arm to disengage the needle from the record and to swing the needle arm to the end of its travel, automatic mechanism controlled by the needle-arm at the end of its travel for effecting the changing of the record, for returning the needle arm to its starting position and for dropping the needle arm to enable the needle to engage the substituted record.

19. In a machine of the kind described, the combination of a rotatable platen to receive a record to be played, a movable needle-arm and needle to cooperate with the record, a magazine having a plurality of pockets to hold records and guided to move so as to bring the pockets in succession to the level of the platen, an ejector arm for engaging a record on the platen to move the same into an empty pocket in the magazine, an injector arm pivotally mounted at the side of the magazine and capable of moving through the pocket which is aligned with the platen to move the record from the pocket onto the platen, means for holding the injector arm out of the magazine to permit the magazine to advance, and automatic means for controlling the ejector arm and the injector arm to effect the changing of the record.

20. In a machine of the kind described, the combination of a rotatable platen to receive a record to be played, a needle-arm and needle to cooperate with the record, a magazine having a plurality of pockets for the different records, automatic means for advancing the magazine to bring the different pockets in succession to the level of the platen, said platen having a movable center-pin, an ejector arm operating to remove the record on the platen and move it into a pocket in the magazine, an injector arm operating with the magazine for moving a record from the magazine out onto the platen, automatic means for controlling the ejector arm and the injector arm and for withdrawing the center-pin and for returning the same to its normal position after the new record is moved onto the platen.

record is in place on the platen, and automatic means for raising the needle arm after the needle-arm has completed its travel and for replacing the needle arm in its starting position with the needle in contact with the substituted record to play the same.

21. In a machine of the kind described, the combination of a magazine, a rack connected with the magazine so as to move when the magazine moves, a pinion meshing with the rack, a shaft carrying the pinion, an escapement device associated with the shaft to permit a single revolution of the shaft, and means for controlling the escapement device to effect a step-by-step advancing movement of the magazine.

22. In a machine of the kind described, the combination of a rotatable platen, a magazine having a plurality of pockets, means for guiding the same to move the pockets successively past the level of the platen, a rack connected with the magazine so as to move when the magazine moves, a pinion meshing with the rack, a shaft carrying the pinion, an escapement device associated with the shaft, a needle arm and needle to cooperate with the record on the platen, automatic means for removing a record from the platen and for moving the same into the magazine, automatic means for moving a record from the magazine onto the platen, automatic means for controlling the escapement to effect the timely movement of the magazine, and automatic means for controlling the needle arm to commence the playing of the new record.

23. In a machine of the kind described, the combination of a rotatable platen, a magazine guided to move vertically past the platen and having a plurality of pockets, a tubular shaft extending downwardly from the magazine, a counter-balancing spring within the tubular shaft for partially supporting the weight of the magazine, a needle arm and needle to cooperate with the record on the platen, automatic means for holding the magazine at different levels to facilitate changing the records, automatic means for moving a record from the platen into the magazine and for moving a new record from the magazine onto the platen, and automatic means for controlling the needle arm to commence the playing of the new record.

24. In a machine of the kind described, the combination of a rotatable platen, a magazine having a plurality of pockets for records and guided to move past the platen so as to bring the pockets successively into alignment with the platen, automatic means for advancing the magazine and controlling the same to facilitate changing a record, means for removing a record from the platen and for placing the same in the magazine, means for removing a record from the magazine and placing the same on the platen, a

driving motor, and means for effecting the return of the magazine actuated by the motor.

25. In a machine of the kind described, the combination of a rotatable platen to receive a record to be played, a magazine guided to move vertically and having a plurality of pockets for the records adapted to align successively with the platen, means for effecting the changing of the record including an injector arm mounted so as to move into the pocket that lies opposite the platen and move the record in the pocket out onto the platen, a motor, means actuated by the motor for returning the magazine to its raised position, and means for preventing the actuation of the last-named mechanism when the said injector arm lies within the pocket.

26. In a machine of the kind described, the combination of a rotatable platen to receive a record to be played, a magazine guided to move past the platen and having a plurality of pockets for the records adapted to align successively with the platen, automatic record changing mechanism including an injector arm mounted so as to move into a pocket lying opposite the platen and move the record in the pocket out onto the platen, a motor, a hand-actuated lever, means actuated thereby for stopping the playing of a record, an automatic stop in the path of said lever for stopping the lever in the position to arrest the playing of a record and activate the record changing mechanism to effect the changing of the record, an automatic latch operating during the operation of the record changing mechanism to stop the operation of the record changing mechanism with the injector arm out of the magazine pocket, automatic means for moving the automatic stop so as to permit a further movement of the said lever, and magazine advancing mechanism having means for connecting the same to the motor by the further movement of the lever.

27. In a machine of the kind described, the combination of a rotatable platen to receive a record to be played, a motor for rotating the platen, a needle arm and needle to cooperate with the record on the platen, an injector arm for removing the record from the platen, an injector arm for moving the new record onto the platen, a slide bar guided to move longitudinally, connected with the injector arm and having means for actuating the injector arm, to effect the removal of a played record and the substitution of the new record, means for actuating the arms by the motor, and means for controlling the actuation of the said arms by the needle arm at the end of its travel.

28. In a machine of the kind described, the combination of a rotatable platen to receive a record to be played, a motor for

rotating the platen, a needle arm and needle to cooperate with the record on the platen, an ejector arm for removing the record from the platen, an injector arm for moving the new record onto the platen, a slide bar guided to move longitudinally, connected with the ejector arm and having means for actuating the injector arm, to effect the removal of a played record and the substitution of the new record, means for actuating the arms by the motor, means for controlling the actuation of the said arms by the needle arm at the end of its travel, a magazine for the records cooperating with the injector arm, and automatic means for controlling the movements of the magazine to bring the records carried thereby successively into alinement with the platen.

29. In a machine of the kind described, the combination of a rotatable platen to receive a record to be played, a motor for rotating the platen, a needle arm and needle to cooperate with the record on the platen, an ejector shaft having an ejector arm to move across the platen and remove the record therefrom, an injector shaft and injector arm carried thereby for advancing a new record onto the platen, automatic means for actuating the ejector shaft controlled by the needle arm at the end of its travel in playing a record, means actuated by the ejecting movement of the ejector arm to move the needle arm to a starting position, a connection between the ejector arm and the injector arm for actuating the injector arm to advance a record onto the platen, and automatic means for lifting the needle off the played record and for setting the same on the new record when the needle arm has been returned to the starting position.

30. In a machine of the kind described, the combination of a rotatable platen to receive a record to be played, a motor for rotating the platen, a needle arm and needle to cooperate with the record on the platen, an ejector shaft having an ejector arm to move across the platen and remove the record therefrom, an injector shaft and injector arm carried thereby for advancing a new record onto the platen, automatic means for actuating the ejector shaft controlled by the needle arm at the end of its travel in playing a record, means actuated by the ejecting movement of the ejector arm to move the needle arm to a starting position, a connection between the ejector arm and the injector arm for actuating the injector arm to advance a record onto the platen, automatic means for lifting the needle off the played record and for setting the same on the new record when the needle arm has been returned to the starting position, a magazine for carrying the records to be played, means for guiding the magazine to bring the records successively to the level of the platen, and

an escapement device operating to give the magazine a step-by-step advancing movement with means for automatically holding the same stationary while the records are being changed.

70

31. In a machine of the kind described, the combination of a rotatable platen to receive a record to be played, a motor for rotating the platen, a needle arm and needle to cooperate with the record on the platen, a magazine having a plurality of pockets for the records, automatic means controlled by the needle arm for synchronously moving the magazine to bring the pockets in succession into alinement with the platen to facilitate the changing of the record, automatic means for setting the needle arm and needle in the starting position, and means corresponding to each pocket operating when the pocket is empty, to move the needle arm, 85 immediately to the end of its travel, to enable it to effect an advance of the magazine, and move the record in the next pocket onto the platen.

75

32. In a machine of the kind described, the combination of a rotatable platen to receive a record to be played, a motor for rotating the platen, a needle arm and needle to cooperate with the record on the platen, a magazine having a plurality of pockets for the records, automatic means controlled by the needle arm at the end of its travel for changing the record and advancing the magazine, a dog carried by the magazine and corresponding to each pocket, having a part 95 mounted so as to be displaced by the record lying in the pocket, a member projecting into the path of the dog when the dog is in the position corresponding to the empty condition of the pocket, and means actuated by 100 said member for moving the needle arm immediately to the end of its travel whereby the automatic mechanism for advancing the magazine operates to advance the magazine to bring the next pocket into alinement with 110 the platen, and operates thereafter to advance a record from the alined pocket onto the platen.

105

33. In a machine of the kind described, the combination of a rotatable platen to receive a record to be played, a motor for rotating the platen, a needle arm and needle to cooperate with the record on the platen, a magazine having a plurality of pockets, automatic mechanism for the magazine operating to move the magazine to bring the pockets successively into alinement with the platen to enable the record to be changed, means for controlling the same by the needle arm at the end of its travel, a dog 115 carried by the magazine corresponding to each pocket and having a part to be engaged by a record in the pocket so as to enable the dog to project when there is no record in the pocket, a pawl in the path of the pro- 120

125

130

jecting dog when the record is absent from the pocket, means actuated by the pawl when struck by the dog for moving the needle arm immediately to the end of its travel and 5 automatic means actuated by the needle at the end of its travel for moving the next record from the magazine onto the platen.

34. In a machine of the kind described, the combination of a rotatable platen to receive a record to be played, a needle arm and needle to cooperate with the record on the platen, automatic means for removing the record after it has been played and for substituting another record therefor, controlled by the needle arm at the end of its travel in playing the record, a manually operated member, means actuated thereby for lifting the needle off the record being played and for returning the needle arm to its starting position, said manually operated member operating to actuate the last named means and move past the same thereafter, and means for returning said last named means to its normal position after actuation by the manually operated member.

35. In a machine of the kind described, the combination of a rotatable platen to receive a record to be played, a motor for driving the same, a needle arm and needle to cooperate with the record on the platen, a stop-lever for arresting the playing of a record, means actuated by the first part of the movement of the stop-lever for lifting the needle off the record being played, a trigger projecting into the path of the stop lever adapted to be actuated and released by the stop lever, means actuated by the trigger for moving the needle arm immediately to the end of its travel, and automatic means 40 controlled by the needle-arm at the end of its travel for removing the record on the platen and for substituting another record therefor, and operating to replace the needle on the new record to play the same.

45. In a machine of the kind described, the combination of the rotatable platen to receive a record to be played, a needle-arm and needle to cooperate with the record on the platen, a counter-shaft normally stationary, a continuously-driven shaft capable of driving the counter-shaft, a stop device controlled by the needle arm at the end of its travel, normally operating to prevent rotation of the counter shaft and operating at 50 the end of the travel of the needle arm to release the counter shaft to permit its rotation, means for effecting connection of the counter shaft to the continuously driven shaft to rotate the counter-shaft through a

single revolution and until it is stopped 60 again by the stop device, and automatic means controlled by the single revolution of the counter-shaft for lifting the needle off the played record, for returning the needle arm to starting position, for changing the record and for setting the needle on the new record to play the same.

37. In a machine of the kind described, the combination of a rotatable platen to receive a record to be played, a needle arm and needle to cooperate with the record on the platen, a stop lever to arrest the playing of a record, means actuated by the first movement of the stop lever for lifting the needle off the record being played, means 70 actuated by the latter part of the movement of the stop lever for moving the needle arm immediately to the end of its travel, and automatic means for changing the record controlled by the needle arm at the end of 75 its travel.

38. In a machine of the kind described, the combination of a rotatable platen to receive a record to be played, a needle arm and needle to cooperate with the record on the platen, a movable magazine for the record, means for advancing the same, automatic means controlled by the needle arm at the end of its travel for removing the record on the platen and substituting a new record 85 therefor from the magazine, a hand operated stop lever for stopping the playing of a record, means actuated by the first part of the movement of the stop-lever for lifting the needle off the record being played, means actuated by the latter part of the movement of the stop-lever for moving the needle arm immediately to the end of its travel whereby the needle arm then actuates the automatic means for changing the record, a motor for driving the platen, means for returning the magazine, and a clutch for controlling said last named means 90 actuated by a further movement of the stop-lever.

39. In a machine of the kind described, the combination of a movable magazine, a shaft, means connecting the magazine and the shaft operating to rotate the shaft when the magazine moves, an escapement device associated with the shaft to permit a step-by-step rotation of the shaft, and means for controlling the escapement device to effect a periodic advancing movement of the magazine.

Signed at Los Angeles, California, this 18th day of August, 1923.

PEYTON ROWAN.
